UNITED STATES PATENT OFFICE.

ANDREW BAXTER, JR., OF BROOKLYN, AND ALBERT MARCHER, OF NEW YORK, N. Y.

DESIGN FOR A CONTAINER OR JAR.

44,163.

Specification for Design.

Patented June 10, 1913.

Application filed March 21, 1912. Serial No. 685,354. Term of patent 7 years.

To all whom it may concern:

Be it known that we, ANDREW BAXTER, Jr., and ALBERT MARCHER, citizens of the United States, residing, respectively, in the borough of Brooklyn, in the county of Kings and State of New York, and in the borough of Bronx, in the city, county, and State of New York, have invented a new, original, and ornamental Design for Containers or Jars, of which the following is a specification, reference being had to the accompanying drawing, forming part thereof.

Figure 1 is a perspective view of a container showing our new design; Fig. 2 is a plan view thereof; and Fig. 3 is a side elevation.

We claim:

The ornamental design for a container or jar, as shown.

ANDREW BAXTER, JR.
ALBERT MARCHER.
